UNITED STATES PATENT OFFICE

WARNER V. HAGBERG, OF MINNEAPOLIS, MINNESOTA

ATTACHMENT FOR DENTAL AND SIMILAR CHAIRS

Application filed February 18, 1928, Serial No. 255,307. Renewed March 6, 1931.

My invention relates to attachments for dental and similar chairs. Heretofore it has been customary to employ separate stools for use by the operator when he wishes to sit down while working on a person occupying the chair. Such stools if kept where they are readily available for use when desired are often in the way and are liable to be knocked over. An object, therefore, of my invention is to provide a seat which is pivotally attached to the chair so that it may be readily swung back out of the way when not in use and the position of which can be readily changed so as to best suit the convenience of the operator. Another object is to provide a device of this character which may be readily attached to existing forms of chairs.

The full objects and advantages of my invention will appear in connection with the detailed description thereof, and the novel features of my inventive idea will be particularly pointed out in the claims.

In the accompanying drawings which illustrate some of the forms in which my invention may be embodied,—

Fig. 1 is a perspective view of a dental chair showing my attachment applied thereto. Fig. 2 is a plan view on an enlarged scale of one form of the device applied to a chair. Fig. 3 is a view in section on the line 3—3 of Fig. 2. Fig. 4 is a view in section on the line 4—4 of Fig. 2. Fig. 5 is a view in section on the line 5—5 of Fig. 2. Fig. 6 is a sectional view of a modified construction. Fig. 7 is a plan view of another modified construction, the seat frame having been removed. Fig. 8 is a view in section on the line 8—8 of Fig. 7.

Referring to the drawings and first more particularly to Figs. 1 to 5, the numeral 10 designates the rotatable column or pedestal of a customary dental chair, this column having a bellshaped member 12 rigid with the top thereof. Projections 14 extend out at diametrically opposite places from the periphery of the member 12. The ends of the projections 14 are provided with trunnions 16 upon which are tiltably mounted bearing members 18 which are customarily secured to the seat frame 20 by bolts. It will be noted that the projections 14 constitute trunnion

supports. In order to apply my device, the aforesaid bolts are removed and replaced by longer bolts 22, these latter bolts extending through a casting 24 which constitutes a portion of my attachment. As will be apparent from Fig. 4, the underside of the bearing member 18 is convexed and as will be apparent from Fig. 5, the projection 14 is of U-channel form so that the underside is U-shaped. The casting 24 on its upper side is concaved to fit the convexed portion of the bearing member and has recesses to receive the flanges of the projection 14 whereby the casting will be firmly held in place when the nuts on the bolts 22 are tightened. The outer end of the casting has a perforated bifurcation 26. The inner end of a seat support 28 is pivotally attached to the bifurcation by means of a pin 30 passing therethrough. The outer end of the support 28 is provided with a boss 32 containing a screwthreaded opening which receives the threads of a screwthreaded rod 34 to the upper end of which a seat 36 is secured. In the form shown in Fig. 6, a member 24' corresponding to the member 24 is formed integrally with the projection 14 instead of being formed separately therefrom and the casting 24' is offset downwardly so as to clear the trunnion 16 and its bearing member. The seat support is attached to the bifurcation 26' in the same manner as before. In the form shown in Figs. 7 and 8, a casting 24'' is provided which is formed separately from the projection 14 but which is offset similarly to the casting 24' shown in Fig. 6. The casting 24'' at its lower end is provided with a lug 38 which fits between the flanges of the projection 14 and the casting is provided with perforated bosses 40. When the casting is in place, a plate 41 is placed over the projection 14. The plate 41 has perforations adapted to register with the perforations of the bosses 40. Bolts 42 passing through the registered perforations serve to hold the casting 24'' firmly to the projection 14. The seat support is attached to the bifurcation 26'' in the same manner as before. In this form the bearing member 18 for the trunnion 16 is held in place on the seat

frame 20 by the original bolts which are not shown in Figs. 7 and 8.

The operation and advantages of my device will be obvious in connection with the foregoing description. The operator may readily swing the seat so as to position it for working to the best advantage and may easily change the height thereof as desired. The device may be conveniently attached to chairs already in use and when thus attached is not in the way of the operator as is the case with ordinary stools now employed.

I claim:

1. In a dental chair including a pedestal with trunnions and supports therefor on the upper end of said pedestal and a seat having bearings tiltably mounted upon said trunnions, an attachment comprising a member extending out from a trunnion support, an auxiliary seat support pivotally attached to the outer end of said member, and a seat carried by said seat support.
2. In a dental chair including a pedestal with trunnions and supports therefor on the upper end of said pedestal and a seat having bearings tiltably mounted upon said trunnions, an attachment comprising a member extending out from a trunnion support, an auxiliary seat support pivotally attached to the outer end of said member, said seat support containing a screwthreaded opening, a screwthreaded rod engaged in said opening, and a seat carried by the upper end of said rod.
3. In a dental chair including a pedestal with trunnions on the upper end of said pedestal and a seat having bearings tiltably mounted upon said trunnions, and at least one of said trunnions having a support in the form of a channel member, an attachment comprising a member adapted to interfit with said channel member, bolt securing said interfitting member to said channel member, an auxiliary seat support pivotally attached to the outer end of said interfitting member, and a seat carried by said seat support.

In testimony whereof I hereunto affix my signature.

WARNER V. HAGBERG.
